(57) **CLAIM**

The ornamental design for a glass tile with a diamond-on-diamond pattern, as shown and described.

DESCRIPTION

FIG. 1 is a perspective view of a design for a glass tile with a diamond-on-diamond pattern;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross section view taken along lines 8-8 of FIG. 2.

The oblique shade lines in the Figures show a transparent, translucent surface, and not surface ornamentation.

The waving shade lines of FIG. 3 show an imperfectly flat surface, and not surface ornamentation.
